UNITED STATES PATENT OFFICE.

SHELDON S. WELLS, OF SHORT HILLS, NEW JERSEY.

RESILIENT WHEEL.

1,162,005.

Specification of Letters Patent. Patented Nov. 30, 1915.

Application filed April 14, 1915. Serial No. 21,189.

To all whom it may concern:

Be it known that I, SHELDON S. WELLS, a citizen of the United States, residing at Short Hills, in the county of Essex and State of New Jersey, have invented certain new and useful Improvements in Resilient Wheels, of which the following is a specification.

This invention relates to resilient wheels for automobiles and the like, and its novelty consists in the construction and adaptation of the parts.

The object of the invention is to produce a wheel which, when the parts are assembled, shall be sufficiently resilient for traction purposes, and at the same time shall be composed of parts which are readily made and assembled and do not require any elaborate machine work in their production.

In the drawings, Figure 1 is a radial section through the felly, outer tire and intermediate parts of a wheel embodying my invention, the section being taken on the plane of the line 1—1 in Fig. 2; Fig. 2 is a side elevation of a portion of the device, some of the parts being shown in section, and parts being broken away to show concealed parts; Fig. 3 is a perspective of a portion of the rim frame; and Fig. 4 is a perspective of one of the socket blocks and the compound lever.

In the drawings, 10 is the felly of the wheel. Closely embracing the same is a circular frame work generally indicated at 11 and comprising three members, namely, a cylindrical member 12, which is in close contact with the felly, and two side members 13 and 14. The cylindrical member 12 is provided with apertures 15 at suitable intervals for the reception of rubber blocks 16 which are provided on their faces with a metal or other sheathing indicated at 17. One of the side members 13 in the form of device illustrated in the drawing is provided with a series of hand holes 18 closed by plates 19 to afford access to the interior of the frame for the purpose of inserting the rubber blocks referred to. Each of the side members 13 and 14 are provided with bearing apertures indicated at 20. An outer flexible rim is made up of a series of socket blocks 21 each provided with projecting trunnions 22 adapted to engage link blocks 23 through projections 24 provided for that purpose. A rubber tire 25 of usual form is placed out-

side of this rim. Each socket block is provided with standards 26 in which is pivoted a lever 27 provided with forks indicated at 28, one of each of the forks being pivoted in turn to the side members 13 and 14. This lever 27 carries a projection 29 at the upper end of which is mounted a roller 30 adapted to contact with the lower sheathed surface of one of the rubber blocks. Also pivoted to the standard 26 is a link 32 having two forks 33 which are pivoted to the side plates 13 and 14 of the frame 11. The lever 27 and link 32 form in effect a means for keeping the direction of movement of the roller 30 substantially radial with respect to the center of the wheel.

In using the device as the several blocks 21 in the rotation of the wheel come in succession immediately above the traction surface, they are pushed radially inward and such motion being transmitted through the standard 26 and lever 27 causes the roller 30 to act against the rubber block 16 to compress it, affording thus a yielding resistance similar to the elastic action of a pneumatic tire. The movement of the link 32 substantially parallel with that of the lever 27 serves to limit and control the extent of the movement of the roller 30 with respect to the block 16. In an entirely similar manner, as each block 21 reaches the point of traction, its corresponding roller is brought into co-operative relation with its corresponding rubber block, and taken as a whole under any usual speed of rotation, the successive action of these co-operating elastic members is equivalent to that of a pneumatic tire.

I claim:

1. A resilient wheel comprising a felly, a rim carried thereby, a series of elastic blocks carried by the rim, a flexible outer rim made up of separate members, and a series of levers intermediate each elastic block and one of the outer rim members whereby the strain of traction is transmitted from the outer rim to such elastic blocks.

2. A series of compressible elastic members arranged circumferentially, a series of inwardly movable members of equal number also arranged circumferentially, and a series of levers pivoted one on each movable member and each adapted to be pressed against that elastic member in radial line with the next movable member of the series.

3. A series of compressible elastic mem-

- bers arranged circumferentially, a series of inwardly movable members of equal number also arranged circumferentially, and a series of levers pivoted one on each movable member and each adapted to be pressed against that elastic member in radial line with the next movable member of the series in combination with a roller between each lever and its coöperating elastic member.
4. A series of compressible elastic members arranged circumferentially, and each secured fixedly in place, a series of inwardly movable blocks united together by alternate links to form a circular flexible rim, and a series of levers pivoted one on each block and adapted to slidably contact with one of the fixed compressible elastic members.
5. A series of compressible elastic members arranged circumferentially, and each secured fixedly in place, a series of inwardly movable blocks united together by alternate links to form a circular flexible rim, and a series of levers pivoted one on each block and adapted to slidably contact with one of the fixed compressible elastic members, in combination with a roller between each lever and its coöperating elastic member.
6. A resilient wheel comprising a series of elastic blocks secured in position around a felly, an outer flexible rim made up of blocks and links, a series of levers pivoted one to each rim block and each adapted to slidably contact with an elastic block and a link connecting each rim block to a frame secured to the felly.
7. A resilient wheel comprising a frame arranged around the felly, elastic blocks carried thereby, an outer circumferential flexible rim consisting of non-elastic blocks and intermediate flexible connections, a lever and a link each pivoted to the frame and one of the elastic blocks and arranged at an angle to the wheel radii, and a member carried by each lever adapted slidably to contact with an elastic block.
8. A resilient wheel comprising a frame arranged around the felly, elastic blocks carried thereby, an outer circumferential flexible rim consisting of non-elastic blocks and intermediate flexible connections, a lever and a link each pivoted to the frame and one of the elastic blocks and arranged at an angle to the wheel radii, and a member carried by each lever adapted slidably to contact with an elastic block, the pivots on the frame being arranged along one radius and the pivots on the block along another radius.
9. A resilient wheel comprising a frame arranged around the felly, elastic blocks carried thereby, an outer circumferential flexible rim consisting of non-elastic blocks and intermediate flexible connections, a lever and a link each pivoted to the frame and one of the elastic blocks and arranged

at an angle to the wheel radii, and a member carried by each lever adapted slidably to contact with an elastic block through an intermediate roller.

10. A resilient wheel comprising a frame arranged around the felly, elastic blocks carried thereby, an outer circumferential flexible rim consisting of non-elastic blocks and intermediate flexible connections, a lever and a link each pivoted to the frame and one of the elastic blocks and arranged at an angle to the wheel radii, and a member carried by each lever adapted slidably to contact with an elastic block through an intermediate roller, the pivots on the frame being arranged along one radius and the pivots on the block along another radius.

11. A resilient wheel comprising a frame arranged around the felly, elastic blocks carried thereby, an outer circumferential flexible rim consisting of non-elastic blocks and intermediate flexible connections, the elastic and non-elastic blocks being identical in number and corresponding in radial position around the wheel, and a series of levers of the same number pivoted one to each non-elastic block and adapted to engage the elastic block next in position in the series.

12. A resilient wheel comprising a frame arranged around the felly, elastic blocks carried thereby, an outer circumferential flexible rim consisting of non-elastic blocks and intermediate flexible connections, the elastic and non-elastic blocks being identical in number and corresponding in radial position around the wheel, and a series of levers of the same number pivoted one to each non-elastic block and adapted to engage the elastic block next in position in the series, and a pivotal connection between each lever and the frame on the felly.

13. A resilient wheel comprising a frame arranged around the felly, elastic blocks carried thereby, an outer circumferential flexible rim consisting of non-elastic blocks and intermediate flexible connections, the elastic and non-elastic blocks being identical in number and corresponding in radial position around the wheel, and a series of levers of the same number pivoted one to each non-elastic block and adapted to engage the elastic block next in position in the series, a series of links one for each lever also pivoted to the non-elastic blocks and to the frame to limit the extent and direction of motion of the non-elastic block.

14. A resilient wheel comprising a frame arranged around the felly, elastic blocks carried thereby, an outer circumferential flexible rim consisting of non-elastic blocks and intermediate flexible connections, the elastic and non-elastic blocks being identical in number and corresponding in radial position around the wheel, and a series of levers of the same number pivoted one to each non-

elastic block and to the frame and having a projection adapted to engage the elastic block next in succession in the series.

15. A resilient wheel comprising a frame arranged around the felly, elastic blocks carried thereby, an outer circumferential flexible rim consisting of non-elastic blocks and intermediate flexible connections, the elastic and non-elastic blocks being identical in number and corresponding in radial position around the wheel, and a series of levers of the same number pivoted one to each non-elastic block and to the frame and having a projection adapted to engage the elastic block next in succession in the series, and a series of links one for each lever and also pivoted to the same parts.

16. A resilient wheel comprising a frame arranged around the felly, elastic blocks carried thereby, an outer circumferential 20 flexible rim consisting of non-elastic blocks and intermediate flexible connections, the elastic and non-elastic blocks being identical in number and corresponding in radial position around the wheel, and a series of 25 levers of the same number pivoted one to each non-elastic block and to the frame and having a projection adapted to engage the elastic block next in succession in the series, and a series of links one for each lever and 30 also pivoted to the same parts and arranged substantially parallel to the levers.

In testimony whereof I affix my signature.
SHELDON S. WELLS.
